PAPER TUBE CONCRETE FORM**Blanding D. Clarkson, Hartsville, S. C., assignor to Sonoco Products Company, a corporation of South Carolina****Application October 12, 1955, Serial No. 540,116****2 Claims. (Cl. 25—118)**

This invention relates to paper tube forms for use in molding concrete columns and the like, and more particularly to an improved paper tube structure for such forms.

U. S. Patent No. 2,677,165, granted May 4, 1954, discloses a multi-ply, spirally wound, paper tube having the innermost ply thereof coated or lined with a polyethylene film for resisting the abrasive action of concrete during pouring, and for covering all protruding fibers of the inner ply to prevent the embedding of these fibers in concrete during setting or curing thereof, so as to facilitate subsequent stripping of the paper tube and adapt it to particular advantage as a concrete form.

According to the present invention, the advantages of a paper tube concrete form as disclosed in the above noted prior patent are improved still further by arranging the structure of the paper tube so that the innermost ply or plies thereof will absorb moisture initially from the poured concrete in a uniform to effect a swelling of the paper tube structure and slight shifting thereof during the initial setting of the concrete, by which swelling and shifting subsequent adhesion of the paper tube to the concrete after setting is eliminated.

This improved result is obtained in accordance with the present invention by perforating the liner coating for the innermost ply of the paper tube uniformly with fine, closely spaced, perforations small enough to prevent release of any of the inner ply protruding fibers from the covering afforded by the liner coating but large enough to allow uniform transfer therethrough of moisture from the concrete to the paper tube structure. The perforations provided for this purpose are in the nature of pin-holes spaced in the order of from about $\frac{1}{16}$ to $\frac{1}{4}$ inch apart, and may be formed in the course of manufacture or after the paper tube structure is fully formed, as desired.

A further feature of the present invention is the arrangement in the paper tube structure of an outer ply, with respect to the innermost coated ply, that is made waterproof so as to serve both as a barrier against penetration of moisture outwardly beyond this outer ply that might result in undue weakening of the paper tube structure, and as a means for retaining and concentrating the absorbed moisture within the inner most plies and thereby insuring a uniform moisture distribution and consequent swelling effect throughout these innermost plies adjacent the concrete being formed.

These and other features of the present invention are described in further detail below in connection with the accompanying drawings, in which:

Fig. 1 is a perspective view of a paper tube concrete form embodying the present invention;

Fig. 2 is an enlarged, fragmentary, sectional detail illustrating diagrammatically a paper tube structure arranged according to the present invention for use in a concrete form as shown in Fig. 1; and

Fig. 3 is a generally corresponding sectional detail

2

illustrating a difference in the forming action of prior art paper tube concrete forms.

Referring now in detail to the drawings, and more particularly at first to Figs. 1 and 2, the concrete form of the present invention comprises a paper tube formed by spirally winding a plurality of paper strips to form a laminated or multi-ply tubular body 10 of the required length and wall thickness, the spirally wound paper strips being bonded by a suitable adhesive interposed between them as they are wound and the wall thickness being proportioned for adequate form strength.

As indicated in Figs. 1 and 2, and as mentioned above, the innermost ply 12 of the paper tube 10 is characterized by a liner coating 14 having a pattern of fine perforations 16 formed therein. This inner ply 12 may be coated in the manner disclosed in the above noted prior patent, and the perforations 16 may usually be formed most conveniently and effectively in the coating 14 directly after it has been applied to the inner ply 12 in advance of the spiral winding operation.

In the spiral wound structure of the completed paper tube 10 (as shown best in Fig. 2), the innermost ply 12 is disposed with the liner coating 14 at the inner face thereof, and is wound with a butt joint. One or more adjacent plies (as illustrated at 18 and 20) are then superimposed by spiral winding with butt joints in staggered relation to form, with the inner ply 12, the structural portion of the paper tube 10 in which moisture is absorbed through the liner coating perforations 16.

The previously mentioned waterproof barrier ply is next applied as illustrated at 22, this ply 22 being wound with an overlapping joint so as to seal it against outward penetration of moisture therethrough. An advantageous form for this barrier ply 22 is a composite arrangement of two paper strips with an asphalt base binder interposed therebetween by which the paper strips are secured together and the whole is rendered waterproof. Outwardly of this waterproof ply 22, such further plies (as 24 and 26) are added as needed to complete the required wall thickness, all additional intermediate plies 24 being wound with butt joints and the final exterior ply 26 being preferably applied with an overlapping joint for covering the outer surface to the best advantage. The relative position of the waterproof barrier ply 22 may be shifted in the structure of the paper tube 10 as desired in dealing with particular circumstances, although it has been found in actual use that consistently good results are obtained when the waterproof ply 22 is arranged as the fourth ply from the inside.

It should also be noted that in arranging the inner coated ply 12, the purpose of using a butt joint is to avoid troublesome disadvantages that result from using an overlapping joint at the inner ply 12, both in stripping the paper tube form from the concrete and in finishing the surface of the formed concrete. An overlapping inner ply joint has a marked tendency to embed in the concrete during forming so as to render subsequent stripping of the form difficult, and further results in impressing a spiral groove corresponding to the width of the overlapping joint in the surface of the concrete that is difficult to remove without a great deal of surface finishing. For these reasons, a butt joint has heretofore been considered preferable in paper tube concrete forms.

However, it is not possible, as a practical matter, to form a butt joint in spiral wound construction of this sort that does not have some spacing between the adjacent edges at the joint. This spacing at the butt joint naturally results in forming a spiral ridge on the concrete surface which, taken alone, is not too objectionable because it can be removed rather easily; but in actual practice a simple ridge does not result at this spacing because

the butt joint cannot be maintained watertight, at least not uniformly. Accordingly, moisture tends to penetrate the butt joint from the concrete during forming and wet the adjacent structure of the paper tube back of the inner ply, causing it to swell so as to undercut the surface of the concrete adjacent the ridge resulting at the butt joint. This is illustrated in Fig. 3, in which concrete is represented at C' being formed by a prior art paper tube form 10' having an inner ply butt joint therein (not shown) resulting in a surface ridge r' in the concrete that has been undercut at each side by swelling of the adjacent paper tube structure, so that removal of the ridge r' will require finishing of the entire concrete surface.

In Fig. 3, the comparable forming action of the paper tube form of the present invention is shown as resulting in a simple ridge r on the surface of the concrete C being formed, this different result being provided by the perforated liner coating 14 on the inner ply 12 that allows uniform wetting and swelling of the entire, inner paper tube structure, rather than just a portion thereof adjacent the inner ply butt joint, and thereby leaves only a simple ridge r on the surface of the concrete C to be removed in finishing.

The present invention has been described in detail above for purposes of illustration only and is not intended to be limited by this description or otherwise except as defined in the appended claims.

I claim:

1. A form for molding circular concrete columns and the like, said form comprising a multi-ply, spirally wound, circular paper tube of sufficient strength and rigidity to support a column of concrete poured therein, the innermost ply of said paper tube being spirally wound with a butt joint and having a liner coating applied thereon that is resistant to the abrasive action of the

concrete during pouring and that covers all protruding fibers of said ply so as to prevent the embedding of said fibers in the poured concrete during setting, said liner coating being perforated uniformly with fine, closely spaced, perforations small enough to prevent release of any of said protruding innermost ply fibers from the covering afforded by said coating, but large enough to allow transfer therethrough of moisture initially from the poured concrete for obtaining a swelling in the structure of said paper tube during the initial setting of the concrete by which subsequent adhesion of said paper tube to the concrete after setting is eliminated, and an intermediate ply of said paper tube being spirally wound with an overlapping joint and being waterproofed to prevent penetration of said moisture outwardly through the structure of said paper tube beyond said intermediate ply.

2. In a multi-ply paper tube having a spirally wound, innermost ply coated for resisting the abrasive action of concrete during pouring and for covering all protruding fibers of said ply and being thereby adapted for use in molding circular concrete columns and the like, the improvement which comprises a coating for said innermost ply that is perforated uniformly with fine, closely spaced, perforations small enough to prevent release of any of the protruding ply fibers but large enough to allow the absorption of moisture from the poured concrete, and an intermediate ply spirally wound with an overlapped waterproofed joint to serve as a barrier against penetration of moisture outwardly therefrom.
